UNITED STATES PATENT OFFICE

160,905

COMBINED BOWLER'S ROUGHENER AND
SHOEHORNWilliam R. Tarrant, Indianapolis, Ind., assignor
of one-half to John Kerinek, Indianapolis, Ind.

Application June 12, 1948, Serial No. 146,931

Term of patent 7 years

(Cl. D34—5)

To all whom it may concern:

Be it known that I, William R. Tarrant, a citizen of the United States and a resident of Indianapolis, county of Marion and State of Indiana, have invented a new, original, and ornamental Design for a Combined Bowler's Roughener and Shoehorn, of which the following is a specification, reference being had to the accompanying drawing, forming a part thereof.

Fig. 1 is a perspective view of a combined bowler's roughener and shoehorn, showing my new design; and

Fig. 2 is a left end view of the combined bowler's roughener and shoehorn shown in Fig. 1.

I claim:

The ornamental design for a combined bowler's roughener and shoehorn, as shown.

WILLIAM R. TARRANT.
